UNITED STATES PATENT OFFICE.

DWIGHT C. CLAPP, OF OWOSSO, MICHIGAN, ASSIGNOR OF ONE-HALF TO
DAVID M. ESTEY, OF SAME PLACE.

FURNITURE-DRAWER.

SPECIFICATION forming part of Letters Patent No. 399,598, dated March 12, 1889.

Application filed September 10, 1888. Serial No. 285,044. (No model.)

To all whom it may concern:

Be it known that I, DWIGHT C. CLAPP, a citizen of the United States, and a resident of Owosso, in the county of Shiawassee and State 5 of Michigan, have invented certain new and useful Improvements in Furniture-Drawers; and I do hereby declare that the following is a full, clear, and exact description of the invention, which will enable others skilled in 10 the art to which it appertains to make and use the same.

This invention relates to furniture-drawers.

The object is to produce a drawer which shall be of such construction that it will be 15 prevented from binding against the guides by any swelling of the same. Furthermore, to produce a drawer which shall be simple of construction, efficient and durable in use, and which shall be comparatively inexpensive of 20 production.

With these objects in view, the invention consists in the improved construction and combination of parts of a furniture-drawer, as will be hereinafter fully described in the 25 specification, illustrated in the drawings, and pointed out in the claim.

In the accompanying drawings, forming part of this specification, and in which like letters of reference indicate corresponding 30 parts, I have illustrated one form of drawer embodying the essential features of my invention, although the same may be carried into effect in other ways without departing from the spirit thereof.

35 In the drawings, Figure 1 is a perspective view of a portion of a bureau, showing my improved drawer in place therein; and Fig. 2 is a detail view of one of the ends.

Referring to the drawings, A designates a 40 bureau which is of the ordinary construction, and is provided with guides 1, on which the drawer B slides. As the drawer forms the essential feature of my invention, I will proceed to describe it minutely.

45 In furniture-drawers of ordinary construction a great deal of trouble is often experienced in opening and closing the same, by

reason of the swelling of the wood-work, and more particularly the sides, which bear upon the top of the drawer-guide and bind it within 50 the bureau, so that it is often necessary to resort to force to open the drawer, which not infrequently results in the disfigurement of the article of furniture in which the drawer is placed.

55 It is the object of this invention to overcome these obstacles in a simple and effective manner; and by reference to the drawings it will be seen that the ends of the drawer are gradually inclined from the front 2 to a point 60 near the back 3, at which point a shoulder, 4, is formed, either by making it integral with the end itself, or by securing it thereto in any suitable manner, as by gluing. This shoulder is designed to be of such a height that its top 65 will fill the opening 5, so that the drawer will be prevented from dropping down or tilting when being drawn out.

It will be seen at a glance that the only portion of the drawer end which comes in contact 70 with the guides is the top of the shoulder, and that if this should have a tendency to bind it will only have to be cut down a little to overcome this. Thus by constructing a drawer on this principle all danger of the 75 same binding in a piece of furniture will be removed, and this construction will be found as cheap as the ordinary methods employed.

Having thus fully described my invention, what I claim as new, and desire to secure by 80 Letters Patent, is—

A drawer having the upper edges of its ends inclined from the front to the back, and having upwardly-projecting shoulders on the inclined edges, the height of which is equal 85 to the highest point of the inclined edge, substantially as described.

In testimony that I claim the foregoing as my own I have hereunto affixed my signature in presence of two witnesses.

DWIGHT C. CLAPP.
